UNITED STATES PATENT OFFICE.

GEORGE PAUL THOMAS, OF GLENSHAW, PENNSYLVANIA.

ANGLE-PLANER.

1,863,625.

Specification of Letters Patent. Patented Dec. 28, 1920.

Application filed July 2, 1919. Serial No. 308,182.

To all whom it may concern:

Be it known that I, GEORGE PAUL THOMAS, residing at Glenshaw, in the county of Allegheny and State of Pennsylvania, a citizen 5 of the United States, have invented or discovered certain new and useful Improvements in Angle-Planers, of which improvements the following is a specification.

My invention relates to metal planers and 10 has particularly to do with planers for cutting or trimming the outer edges and the heels of angles such as are use in the construction of steel bridges, buildings, ships, etc.

15 The object of my invention is to provide an angle planer whereby deep cuts may be simultaneously made upon the outer edge or edges and upon the heel of different sized angles, each angle being engaged and fed to 20 the cutter during the planing operation in such a manner that it will not be bent or otherwise distorted.

In the accompanying sheets of drawings, 25 which form part of my specification, the preferred embodiment of my invention is illustrated. Figure 1 is a side elevation of the angle planer; Fig. 2 a plan view thereof; Fig. 3 an elevation of the right end of the machine as viewed in Fig. 1; Fig. 4 a view 30 of the reducing gearing of the driving connections, the plane of view being indicated by the line IV—IV Fig. 3; Fig. 5 a view of the driving connections of the various feed rollers, the plane of view being indicated by 35 the line V—V, Fig. 3; and Fig. 6 a side view of the general arrangement and construction of feed rollers, cutters and guides, the plane of view being indicated by the line VI—VI, Fig. 3.

40 In the machine which I provide, an angle to be planed is fed longitudinally by and between a plurality of pairs of feed rollers, between which pairs several cutters are arranged in positions to plane the heel and 45 edges of the angle.

While various numbers of pairs of feed rollers may be used, I preferably provide three pairs constructed and arranged in the manner particularly indicated in Fig. 6. 50 These rolls may be designated as entering rolls 1 and 1^a, intermediate rolls 2 and 2^a, and discharge rolls 3 and 3^a. As seen clearly in Fig. 3, the rolls of each pair are preferably provided with coöperating concave and 55 convex conical faces adapted to engage both sides of both legs of an angle 4. The rolls

having concave faces may be the upper rolls 1, 2 and 3, and the rolls having the convex faces the lower rolls 1^a, 2^a and 3^a. To facilitate the gripping of an angle, the faces of 60 the rolls may, as indicated, be suitably roughened. Between the entering and intermediate pairs of feed rolls there is arranged a vertically adjustable cutter 5 adapted to plane the heel of an angle, and 65 between the intermediate and discharge pairs of rolls there are arranged two adjustable cutters 6 and 7 for planing the outer edges of the legs of an angle. These cutters may be of any shape depending upon the 70 character of cut desired to be made.

With further reference to the parts of the angle planer which act directly upon an angle as it passes through the planer, there 75 may be provided a downwardly inclined grooved shoe 8 at the discharge side of the entering rolls 1 and 1^a, adapted to direct downwardly the forward end of an entering angle so that the heel of the angle may be properly positioned with respect to the heel 80 cutter 5. Below the cutter 5 there is an idle roll 9 adapted to hold the angle firmly against such cutter. Between the intermediate and discharge pairs of rolls there are upper and lower idler rolls 10 and 10^a for 85 firmly holding an angle in proper position to be operated upon by the edge cutters 6 and 7. Finally, at the discharge side of the pairs of rolls 3, 3^a there is provided a vertically adjustable straightening roll 11 90 adapted to prevent the angle from bending upwardly.

The several rolls and cutters thus far explained are mounted in a frame which preferably comprises a bed-plate 12 and three 95 vertically disposed parallel housings 13, 14 and 15. Both the upper and lower feed rolls of the three pairs thereof are positively driven and to such end each feed roll is mounted upon a shaft having bearings in 100 each of the three housings. The shafts for the upper rolls are indicated by the numerals 16, 17 and 18, and those upon which the lower rolls are mounted by the numerals 16^a, 17^a, and 18^a. The driving connections for 105 these rolls will be presently explained.

That the planer may be used for planing angles of different thicknesses, means are provided for adjusting the coöperating feed rolls with respect to each other. To such 110 end, in the illustrative embodiment of my invention, provision is made for adjusting

the upper feed rolls. For such purpose each bearing in the frame housings 13, 14 and 15 for the several shafts 16, 17 and 18 consists of a vertically slidable pillow block 19, to the upper side of which there are attached rods 20 extending through suitable openings formed in a plate 21 secured to the end of a screw 22. Between the block 19 and plate 21 there is a strong coil spring 23, the initial compression of which is effected by tightening nuts 24 on the outer ends of rods 20. At the upper end of each of the screws 22 there is a worm wheel 25 secured to a sleeve 65 interiorly threaded to engage the threads of the screw 22. Hence, by rotating the worm wheels, the screws 22 may be raised or lowered to adjust the position of the blocks 19. The adjustments of the shafts 16, 17 and 18 are preferably effected separately by independently operated mechanism. In Fig. 2 it will be seen that the worm wheels 25 for adjusting the three bearings of the shaft 16 each mesh with a worm formed or mounted on an adjusting shaft 26 provided at its end with a hand wheel 27. In a similar manner adjusting shafts 28 and 29 each have independent operating wheels 30 and 31 for adjusting the feed roll shafts 17 and 18.

The means for positively driving each of the several feed rolls are such that the required, necessarily large, driving torque may be applied to each of the roll shafts in their various adjustable positions relative to each other. Preferably each roll shaft is provided with a pinion, the upper shafts 16, 17 and 18 being provided with pinions 36, 37 and 38, respectively, and the lower roll shafts 16^a, 17^a and 18^a with pinions 36^a, 37^a and 38^a. Arranged between adjacent roll shaft pinions and rotatably mounted in the frame housing 15, there are idler pinions 39, 39^a, 40 and 40^a. The pinion 39 meshes with the roll shaft pinions 36 and 37, the pinion 39^a meshes with the roll shaft pinions 36^a and 37^a, and pinions 39 and 39^a also mesh with each other.

To the end that the rolls 1, 2 and 3 (and particularly roll 2) may be freely moved vertically, to effect the adjustment already described, and at the same time maintaining through their pinions driving connection with the source of power, the succession of driving pinions 36, 39, 37, 40 and 38 is arranged not in a common plane but in two planes (compare Figs. 2 and 5) pinions 36, 39 and 37 lying in one plane and pinions 32, 40 and 38 in another plane, pinions 32 and 37 being both of them keyed to the shaft 17. The succession of pinions forming the lower sequence namely pinions 36^a, 39^a, 37^a, 40^a and 38^a may however all be in a common plane, for it is not requisite respecting any of them that it be moved relatively to the others. The pinions being arranged as is particularly shown in Figs. 2 and 5, it will be understood that the function of pinion 40^a

is to drive shaft 18^a and no other. Shaft 18 is driven from shaft 17 through pinions 32, 40 and 38.

To this arrangement of driving pinions power is applied preferably through one of the roll shafts, and, as shown in the drawings, the power may be applied to the roll shaft 16^a, the power being supplied by a motor 41 mounted upon the bed-plate 12. Between the pinion 42 on the armature shaft of the motor and the feed roll shaft 16^a there is a train of reducing gears shown particularly in Fig. 4, such train of gears consisting of a pinion 43 meshing with the pinion 42, shaft 44, pinion 45, pinion 46, shaft 47, 80 pinion 48 and pinion 49, which latter pinion is keyed to the feed roll shaft 16^a.

It will be observed with respect to the driving connections that the rotation of the pinion 36^a in a direction to feed an angle 85 from right to left will, through the arrangement of pinions indicated in Fig. 5, cause all of the feed rolls to be rotated in the required direction for thus feeding an angle. Furthermore, by reason of the fact that the 90 axes of rotation of the upper series of pinions and their points of intermeshing as well lie all in a substantially common plane, the roll shafts 16, 17 and 18 may, without impairing the effectiveness of the interlocking or meshing of the pinion teeth, be vertically adjusted sufficiently to permit the feed rolls to engage angles of the usual range of thickness.

As previously stated, the heel cutter 5 is preferably arranged between the first two 100 pairs of feed rolls, and the edge cutters 6 and 7 between the second and third pair of feed rolls. By thus arranging the cutters the heel and both edges of an angle may be planed from end to end of the angle. 105 Furthermore, it should be noted that the edge cutters offer greater resistance to the advance of the angle than does the heel cutter. Hence, by placing the edge cutters between the second and third pairs of rolls, greater propelling or feeding power will be applied to the angle at the point of greater resistance to its advance.

For adjusting the heel cutter 5, such cutter may be mounted upon the end of a screw 115 50 adapted to be vertically adjusted by means of a worm wheel 51 and worm shaft 52 which may be rotated by a hand-wheel 53.

As will be seen from Fig. 3, the edge cutters 6 and 7 are mounted, respectively, on 120 longitudinally movable screws 54 and 55, which extend in planes substantially parallel to the planes of the legs of an angle passing between the feed rolls. The cutter 6 may be adjusted by means of a hand wheel 56 arranged on the outside of the vertical frame 13. That the cutter 7 may be independently adjusted from the same position, the outer end of its adjusting screw 55 is provided with a spiral pinion 57 meshing with a spiral 130

pinion 58 secured to a shaft 59, which shaft extends through the frame housings 13 and 14, and is provided on its outer end with a hand wheel 60.

5 As previously stated, the coöperating pairs of feed rolls are provided with convex and concave conical faces adapted to bear upon both sides of both legs of an angle. By so shaping the feed rolls the same feeding 10 pressure will be applied to each leg of an angle with the result that both legs will, if elongated at all by reason of such pressure, be elongated the same amount. Accordingly, there will be no tendency of the angle to 15 bend laterally. In case of any tendency of the angle to bend upwardly, such tendency may readily be counteracted by means of the straightening roll 11 arranged at the discharge side of the feeding rolls 3 and 3^a. 20 As seen in Fig. 1, the straightening roll 11 is mounted for vertical adjustment, a hand wheel 61 being provided for this purpose. It will be understood that the straightening roll 11 will be so positioned vertically that 25 it will bear down upon the back of an angle sufficiently to remove any upward bend or kink that may result from the pressure of the feed rollers.

With respect to the mounting and adjustment of the several guides between the 30 pairs of feed rolls, the shoe 8 may be provided with an upwardly extending plate 65 connected to a chuck 66 in which the heel cutter 5 is carried. Preliminary ad- 35 justment of the shoe with relation to the chuck may be effected by providing the plate 65 with vertically disposed slots adapted to receive bolts 68 engaging the chuck. The guide rolls 9 and 10^a may either 40 or both be mounted on eccentric bearings such as 69, which, after having been preliminarily adjusted to the required position, may be held in such position by means of a set screw 70. Guide roller 10 may be ver- 45 tically adjusted by means of a hand wheel 71 secured to a screw 72 having threaded engagement with a trunnion 73 in which the roller 10 is rotatably mounted.

In the operation of the angle planers, the 50 feed rolls, cutters and idle roller 10 are first adjusted according to the size of the angle to be planed and the depth of cuts to be made upon such angle. For adjusting the feed rolls the several shafts 26, 28 and 29 may be turned independently by means of the hand wheels connected to the shafts. For indicating the positions of these rolls, the blocks 19 may each be provided with a pointer 62, and the portion of the housing 55 13 adjacent thereto may be provided with a scale 63. The adjustment of heel cutter 5 and shoe 8 is effected by turning the hand wheel 53, the adjustment of the edge cutters 6 and 7 by turning the hand wheels 56 60 and 60, respectively, and the adjustment of

the idle roller 10 by turning the hand wheel 71.

The machine having been thus adjusted, the forward end of an angle to be planed is placed in the grip of the entering pair of rolls 1 and 1^a. These rolls feed the angle forwardly, the forward end of the angle being guided by means of the shoe 8 to a proper position with respect to the heel cutter 5. In the further advance of the angle 75 the forward end is engaged by the intermediate rolls 2 and 2^a, and is finally engaged by the discharge rolls 3 and 3^a. Between the grip of the three pairs of feed rolls the angle is continuously fed forwardly and its heel and edges continuously planed by the the cutters. It will be understood that in case it is not desired to plane the back and both edges of an angle, only such cutters need be used as are required 80 to effect the desired planing.

According to the provision of the patent statutes, I have described the principle and operation of my invention together with the construction which I now consider to 90 represent the best embodiment thereof. However, I desire to have it understood that, within the scope of the appended claims, my invention may be practised by other forms of construction than that specifically shown and described herein.

I claim is my invention:

1. In an angle planer the combination with a stationary cutting tool of means for feeding the material to the tool including 100 a pair of conically surfaced convex and concave rolls forming a roll pass of the shape of the angle to be operated on, and an abutment arranged on the delivery side of the roll pass and adapted to be engaged by 105 and to prevent the bending of an advancing angle, substantially as described.

2. In an angle planer, the combination of three successively arranged pairs of feed- 110 ing rolls, the rolls constituting each pair being movable with respect to each other, means for positively driving each of said rolls, a heel cutter arranged between the first and second pairs of rolls, and edge cutters arranged between the second and 115 third pairs of rolls.

3. In an angle planer, the combination of three pairs of successively arranged feed- 120 ing rolls, each pair having coöperating con- 125 cave and convex conical faces adapted to engage both sides of both legs of an angle, means for driving said rolls, a heel cutter arranged between the first and second pairs of rolls, edge cutters arranged between the second and third pairs of rolls, and an ad- justable straightening roll at the discharge side of the third pair of rolls adapted to bear upon the back of one angle as it emerges from the planer.

4. In an angle planer, the combination of 130

three pairs of successively arranged feeding rolls each mounted upon a shaft provided with a driving pinion, each pair of rolls having coöperating concave and convex conical faces adapted to engage both sides of both legs of an angle, a motor, driving connections from said motor to one of said roll shafts, pinions meshing with said driving pinions whereby each of said rolls may be positively driven, means for adjusting one roll of each pair of rolls with relation to its coöperating roll, and cutters arranged between pairs of rolls.

5. In an angle planer, the combination of three pairs of feeding rolls arranged in tandem and each roll being mounted on a shaft provided with a pinion, each pair of rolls consisting of an upper and lower roll having coöperating concave and convex conical faces adapted to engage both sides of both legs of an angle, means for adjust-

ing one roll of each pair of rolls with relation to its coöperating roll, a motor, driving connections from said motor to one of said roll shafts, rotatably mounted connecting pinions meshing one with the driving pinions of adjacent upper roll shafts and one with the driving pinions of adjacent lower shafts, the axes of rotation of the adjustable roll pinions and of the connecting pinions meshing with them lying substantially in a common plane parallel with the line of feed between the rolls, a heel cutter between the first and second pairs of rolls, and edge cutters between the second and third pairs of rolls.

In testimony whereof I have hereunto set my hand.

GEORGE PAUL THOMAS.
